CLAIM

The ornamental design for a shoe outsole bottom as shown and described.

DESCRIPTION

FIG. 1 is a bottom perspective view of a shoe in accordance with our new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof; and,

FIG. 7 is a bottom plan view thereof.

Broken lines shown in the drawing represent portions of the shoe outsole bottom, the shoe midsole periphery and the environmental structure of the shoe upper which form no part of the claimed design.

1 Claim, 7 Drawing Sheets
